United States Patent Office.

DAVID A. MANUEL, OF NAPA CITY, CALIFORNIA.

Letters Patent No. 77,630, dated May 5, 1868.

IMPROVED SIDE-HILL PLOUGH.

The Schedule referred to in these Letters Patent and making part of the same.

TO ALL WHOM IT MAY CONCERN:

Be it known that I, DAVID A. MANUEL, of Napa City, county of Napa, State of California, have invented an Improved Reversible Side-Hill Plough; and I do hereby declare the following description and accompanying drawings are sufficient to enable any person skilled in the art or science to which it most nearly appertains to make and use my said invention or improvements without further invention or experiment.

The nature of my invention is to provide a reversible side-hill plough, so constructed that the mould-board is divided above the point, and the two parts pivoted to the front and rear of the standards and frame, so that, by turning from right to left or left to right, a perfect plough is formed without alteration to the beam.

To more fully illustrate and explain my invention, reference is had to the accompanying drawings, forming a part of this specification, of which—

Figure 1 is a top view,

Figure 2 is a bottom view, and

Figure 3 is a side elevation.

Similar letters of reference in each of the figures indicate like parts.

A represents the land-side of my plough, made considerably longer than that of the ordinary plough, and is tapering from the centre to the heel. The opposite end or point is bevelled flatwise at the top, and is made wider than at the heel, for the purpose of keeping the plough to the land. A lug or projection, B, is made at the extreme end of the point, so that as the plough-point is changed from right to left, it will lock against it, and form a close and smooth bevelled joint, the rear part of the faces of the points being cut away, and the end of the land-side chamfered for that purpose.

A broad standard, C, is placed back of the point of the land-side, at the top of which is attached a flat bar, D, bent downward to near the heel of the land-side, where it is held by a post, E.

The plough-point and share F, when removed from the mould-board, is nearly triangular in form, and has two cutting-points, G and G', and is hinged to the standard by a pivot, H, passing through it, and an arm, I, into the land-side, which allows it to swing to the right or left about one-quarter of a circle, at which point it is locked against the land-side.

The mould-board J is riveted to the long arm K, which is hinged to the post E at the rear end of the land-side, and, when brought in position against the share, forms a perfect plough, the two parts coming in contact, where it is held by hooks or lugs, at the end of rods L L, which slide up and down back of the mould-boards into holes L' L' at the side of the point or share. The rods cross each other diagonally above the arm K, and are bent at right angles for convenient handles for the driver.

The handles may be attached to the broad standard, and be out of the way of the swinging mould-board. The beam may be attached to the flat bar.

In operating with my plough, at the end of the furrow, the rod which holds the two parts together is drawn up, and the point turned to its place at the opposite angle by its hold in the soil, when the mould-board is caused to swing around on its axis by the driver, to the point or share, where its locked and prepared for turning another furrow.

Having thus described my invention, what I claim, and desire to secure by Letters Patent, is—

1. Dividing the plough, between the share and mould-board F and J, and hinging the two parts to the land-side and standards, so that by swinging them to the right or left, and joining the two said parts, they will form a perfect plough, substantially as described.

2. Construction of the land-side A, wider in front than at the heel, so that the line of draught will incline towards the land, substantially as described.

In witness whereof, I have hereunto set my hand and seal.

DAVID A. MANUEL. [L. s.]
